John W. Snowdon
ATTORNEY

UNITED STATES PATENT OFFICE

2,366,605

BLOWTORCH

John Louis Evans, Pine Bluff, Ark.

Application April 1, 1943, Serial No. 481,476

2 Claims. (Cl. 158—76)

This invention relates to blow torch burner construction, the primary object of the invention being to provide a burner wherein perfect combustion will be insured, for the efficient operation of the burner.

An important object of the invention is to provide a burner including a fuel nozzle and an air nozzle, so arranged with respect to each other, that a jet of air is directed through the fuel issuing from the fuel nozzle, at right angles to the path of travel of the fuel, resulting in effecting a complete atomizing of the oil and perfect mingling of the oil with the air, forming a highly combustible mixture.

Still another object of the invention is to provide a burner including a curved air nozzle located directly over the fuel nozzle, the curved nozzle providing a hood against which a fine stream of fuel is directed, whereby the fuel is divided and caused to swirl on its passage through the air jet.

With the foregoing and other objects in view, which will appear as the description proceeds, the invention resides in the combination and arrangement of parts and in the details of construction hereinafter described and claimed, it being understood that changes in the precise embodiment of the invention herein described, may be made within the scope of what is claimed, without departing from the spirit of the invention.

Referring to the drawing:

Figure 1 is a longitudinal sectional view through a burner shield, illustrating the burner block, constructed in accordance with the present invention, as mounted in one end thereof.

Figure 2 is an end elevational view of the burner.

Figure 3 is a vertical sectional view through the burner block illustrating the air and fuel nozzles.

Figure 4 is a sectional view taken on line 4—4 of Figure 3.

Referring to the drawing in detail, the reference character 5 indicates the burner shield of the device, the end wall 6 thereof being bored to receive the burner block 7 which is shown as fitted therein.

The burner block is formed with an upper bore in which the air pipe 8 is positioned and through which air enters the air nozzle 9 which is positioned in the inner end of the bore so that the inner end of the nozzle 9 extends into the burner shield.

As clearly shown by Figure 3 of the drawing,

the inner end of the nozzle 9 is beveled, providing a hood 10 which is formed with a curved wall.

The fuel pipe 11 extends into the lower bore of the burner block and through which fuel is supplied to the burner proper. An extension 12 is formed on the burner block, the extension being of a length to extend an appreciable distance within the burner shield 5.

Formed in the wall of the extension 12, and disposed directly under the hood 10, is an orifice 13 through which a fine stream of fuel is directed to the curved surfaces of the hood 10. Because of the curved surfaces of the hood 10, it will be seen that the fuel, as it strikes the curved surfaces, will be caused to split and follow the curved surfaces with the result that the fuel takes a swirling movement in a direction at right angles to the jet of air, passing through the hood, resulting in effecting a complete atomizing of the oil and perfect mingling of the oil or fuel with the air, insuring perfect combustion.

The inner end of the extension 12 is closed by means of the plug 14 which may be removed for the purpose of cleaning the burner.

25 The supporting band indicated at 15 is secured to the end wall 6 of the burner shield, adjacent to the burner opening thereof, and provides a support for the burner block 7. The supporting band is formed with a threaded opening in which 30 the bolt 16 operates to contact the burner block and hold the burner block in position within the burner opening. By removing the bolt 16 it will be obvious that the burner block may be readily removed to facilitate the cleaning and repairing 35 of the burners.

From the foregoing it will be seen that due to the construction shown and described, I have provided a burner which will completely atomize the oil or fuel, insuring perfect combustion, for the purpose described.

What is claimed is:

1. A burner comprising a tubular shield having ventilating openings formed in the wall thereof, an end wall closing one end of the shield, a burner block having an extension fitted in an opening of the end wall, said burner block having superimposed horizontal bores, an air pipe extending into the uppermost bore, the inner end of the air pipe being upwardly inclined from the lower side to the upper side thereof, providing a transversely curved hood, said extension having an orifice formed in the upper surface thereof and adapted to direct a stream of fuel into the hood against the curved surface thereof, at right angles to the flow of air through said hood, and

means for adjustably supporting the burner block on the tubular shield.

2. A burner comprising a tubular shield having openings in the wall thereof, an end wall closing one end of the shield, said end wall having an opening, a burner block positioned within the opening of the end wall of the shield, said burner block having superimposed horizontal bores, an air pipe extending through the uppermost bore of the burner block, the inner end of said air

pipe extending an appreciable distance beyond the inner end of the burner block, the lower portion of said inner end of the air pipe being cut away providing a hood, said burner block having 5 a vertical bore communicating with the lowermost bore of the burner block and through which a stream of fuel may be directed into a stream of air at right angles to the flow of air into the burner shield.

10

JOHN LOUIS EVANS.
